UNITED STATES PATENT OFFICE.

MYRON S. WALL, OF BERKELEY, CALIFORNIA, ASSIGNOR TO STANDARD OIL COMPANY, OF SAN FRANCISCO, CALIFORNIA, A CORPORATION OF CALIFORNIA.

DESIGN FOR A SIGN.

Application filed May 14, 1921. Serial No. 469,564. Term of patent 14 years.

To all whom it may concern:

Be it known that I, MYRON SHARMAN WALL, a citizen of the United States, residing in Berkeley, the county of Alameda, State of California, have invented a new, original, and ornamental Design for a Sign or Use in Advertising an Article of Manufacture, of which the following is a specification, reference being had to the accompanying drawing, forming a part thereof.

The figure is a plan view of a sign showing my new design.

I claim:

The ornamental design for a sign as shown.

M. S. WALL.
